UNITED STATES PATENT OFFICE.

ERNST BLATTMANN, OF BERLIN-NONNENDAMM, GERMANY, ASSIGNOR TO SIEMENS & HALSKE A. G., OF BERLIN, GERMANY, A CORPORATION OF GERMANY.

SPARK-PLUG.

1,181,425.

Specification of Letters Patent.

Patented May 2, 1916.

Application filed September 3, 1913. Serial No. 787,989.

To all whom it may concern:

Be it known that I, ERNST BLATTMANN, a German citizen, and resident of Berlin-Nonnendamm, Germany, have invented certain new and useful Improvements in 5 Spark-Plugs, of which the following is a specification.

This invention relates to a spark plug for combustion engines, in which the middle 10 electrode is provided with a bore-hole separated from the exterior air, the discharge opening of said bore-hole being opposite to an electrode for choking off the discharge gas.

15 The drawing shows in a cross-section one form of a spark plug according to my invention.

1 is the middle electrode having a bore-hole 2 which is shown dotted, 3 is the electrode which is mounted in the casing 5, and 20 4 and 6 are insulating bodies. During the operation of the present spark plug at each compression stroke a combustible mixture is pressed into the bore-hole 2 which mixture, 25 when discharging through the bore-hole, will be ignited and throttled at the spark gap by the counter-electrode 3. The blasting effect due to the discharge of the gas will thus keep the points of the spark gap 30 always in a clean condition. In order that the hollow electrode may not become too hot during operation, it is advantageously surrounded by an insulating body 4 which is of such form and dimensions that between electrode and insulating body a small space will 35 be left free. This middle electrode is made conical at its lower end, in order to obtain a broad spark and in order to prevent the formation of scrap at the spark points. The

deposit of scrap, otherwise, may eventually become so large that it will cause a short-circuit with the counter-electrode.

The counter-electrode 3 which is mounted in the interior of the casing 5 shall remain entirely within this casing and be protected against injury. For this purpose the counter-electrode is mounted in a cut-out of the casing 5. Since in this case the spark points are positioned in the interior of the casing and covered up from underneath by the electrode which is inserted into the casing, one or more openings 7 are provided through which the distance of the electrodes may be observed and adjusted from the side if desired.

Having thus described my invention I herewith claim as new and desire to secure by Letters Patent of the United States:—

A spark plug consisting of a casing, an electrode mounted centrally therein, said electrode having an unencumbered bore at its projecting end, said bore extending to a certain depth only of said electrode, a second electrode disposed opposite to and at suitable distance from the discharge opening of said bore to throttle the gas discharging therefrom during expansion and one or more openings in the wall of said casing for adjusting and observing the distance between said electrodes.

In witness whereof I have hereunto set my signature in the presence of two subscribing witnesses.

ERNST BLATTMANN.
